CLAIM

The ornamental design for a blister package, as shown and described.

DESCRIPTION

1. Blister package
1.1 is a front elevation view of a blister package showing my new design;
1.2 is a rear elevation view thereof;
1.3 is a right side view thereof;
1.4 is a left side view thereof;
1.5 is a top view thereof;
1.6 is a bottom view thereof; and
1.7 is an upper front perspective view thereof.
The portions of the blister package shown in broken lines form no part of the claimed design.
